Term of patent 14 years

(Cl. D57—1)

FIG. 1

FIG.4

FIG. 1 is a front perspective view of a sun visor embodying my new design;

FIG. 2 is a back perspective view of the sun visor of FIG. 1;

FIG. 3 is a front perspective view of another embodiment of the design shown in FIGS. 1 and 2, it being understood that the stippled shading is intended to indicate contrast with the unshaded border portion of the sun visor; and

FIG. 4 is a back perspective view of the sun visor of FIG. 3.

The broken line showings of the wearer in FIGS. 1 and 3 of the drawing are for illustrative purposes only.

I claim:

The ornamental design for a sun visor or similar article, substantially as shown and described.
